UNITED STATES PATENT OFFICE

138,710

DESIGN FOR A DRY CLEANING SPOTTING UNIT

Don O. Goodwin, St. Louis, Mo.

Application April 22, 1944, Serial No. 113,337

Term of patent 14 years

(Cl. D49—1)

To all whom it may concern:

Be it known that I, Don O. Goodwin, a citizen of the United States, residing at St. Louis, in the city of St. Louis and State of Missouri, have invented a new, original, and ornamental Design for a Dry Cleaning Spotting Unit, of which the following is a specification, reference being had to the accompanying drawing, forming part thereof, in which the figure is a perspective view of a dry cleaning spotting unit, showing my new design.

The back of the cabinet is plain and the end thereof not shown is substantially like the end shown in the figure.

I claim:

The ornamental design for a dry cleaning spotting unit, substantially as shown and described.

DON O. GOODWIN.
